GARMENT HANGER

Angelo D'Ambrosio, Herkimer, N. Y.

Application May 10, 1949, Serial No. 92,417

7 Claims. (Cl. 223—88)

1

This invention relates to garment hangers, and more particularly to a device of that character by means of which clothing such as trousers and skirts may be suspended from one end, as from the waistband so as to hang freely.

One feature of this invention is a garment hanger of generally triangular shape which will support the coat on the sloping arms in the usual manner and which is also provided with horizontally slidable yieldable members which may be placed within the waistband of a pair of trousers, or a skirt to hold the garment by frictional pressure, allowing the rest of the garment to hang freely so that wrinkles or creases will be removed.

Another feature of this invention is a hanger device provided with adjustable members for frictional engagement with the inner surface of a garment which is to be suspended which may be used with garments of widely varying dimensions.

And with the above and other features in view, this invention resides in the novel features of form, construction, arrangement and combination of parts described and claimed, and illustrated in the accompanying drawings, in which:

Fig. 1 is an elevational view of a preferred form of the invention;

Fig. 2 is a plan view of the preferred form of the invention;

Fig. 3 is a cross-section taken on the line 3—3 of Fig. 1;

Fig. 4 is a cross-section taken on the line 4—4 of Fig. 1;

Fig. 5 is an end view of a preferred form of spring means used in the device;

Fig. 6 is an elevational view of a modified form of garment hanger;

Fig. 7 is a cross-section taken on the line 7—7 of Fig. 6;

Fig. 8 is a cross-section taken on the line 8—8 of Fig. 6; and

Fig. 9 is an enlarged cross-section of a portion of the housing interior taken on the line 9—9 of Fig. 6.

Referring now to the drawings in detail, a bow member is indicated at 10, having a conventional swiveled suspension hook 11 at its vertex. Attached between the lower ends 10a and 10b of the bow member is a horizontal supporting member 12. Running along the lower side of the member 12 is a longitudinal recess 13, and slidably received in this recess are the enlarged upper margins 14 of a pair of downwardly extending flat garment engaging members 15. The lower margins 12a and 12b of the recess 12 are

turned inwardly so as to engage with the enlarged marginal portions 14 and thus provide a trackway for slidably supporting the members 15. Depending centrally of the horizontal support member 12 there is provided an elongated housing 16 into which the members 15 may be telescoped, and within the housing there is carried a yieldable means such as the coil spring 17. Preferably this spring will be formed with a substantially rectangular outline as shown in Fig. 5, and the end turns 17a and 17b are preferably formed so as to lie flat against the inner face of the members 15 in order to exert an outward pressure against the members which is substantially equalized over the area. The members 15 may be provided at their outer edges with finger elements 15a to afford a more positive engagement with the inner surface of a garment which is to be supported.

In using this garment hanger it is only necessary to grasp the two garment-engaging members 15 and press them inwardly into the housing 16 against the pressure of the spring 17 after which they may be inserted into the waistband of a garment to be supported. When the members 15 are released the spring will force them outwardly until the elements 15a will frictionally engage the inner surface of the waistband. A garment hung in this manner will not become wrinkled or creased; in fact, if there are wrinkles in a garment there will be a tendency for them to disappear when the garment is hung in this manner.

In Figs. 6—9 there is shown a modified form of my invention which utilizes a somewhat different expansion means for urging outwardly a pair of garment-engaging members 24, which are similarly provided with finger elements 25, and an enlarged upper margin 26 which is slidably supported by the inwardly turned margins 12a and 12b in the recess 13. Centrally contained within the housing 16 there is provided a vertical block 18 which supports a rod 19 below the horizontal support 12 and in spaced parallel relationship to it. The members 24 are also provided with longitudinally extending bores 20 in alignment with the rod 19 so that one may be telescoped within the other. The length of the rod is such that when the members 24 are at their outward limits it will project a slight amount into the bores 20. The yieldable means in this modification is a coil spring 21 which encircles the rod 19, and at one end abuts against the block 18, while at the other end is seated on a shoulder 22 formed by a counterbore 23 in the members 24.

In making this device many suitable materials

may be employed such as metal or wood, but preferably plastic materials may be used. The separate elements can be cast, or extruded, and joined together by suitable cement. It should be understood that changes and modifications in the form, construction and arrangement of the several parts may be made.

I claim:

1. In a garment hanger of the class described, a horizontal trackway, a pair of garment-engaging members provided with means at their upper portions for slidable suspension in said trackway and having garment engaging portions located on a level below said trackway, an open ended housing depending from a central portion of said trackway in alignment with the garment-engaging members and into which said members may be telescoped, and means in the housing and at a level below said trackway yieldably urging said members outwardly.

2. In a garment hanger of the class described, a pair of elongated flat garment-engaging members having an enlarged portion at the upper margin, a horizontal support member provided with a longitudinally extending recess along its under side, an open ended housing into which said garment-engaging members may be telescoped depending from a central portion of the horizontal support member, yieldable means carried within the housing for urging the garment-engaging members outwardly, said recess in the horizontal support member having inwardly turned marginal portions outwardly of the housing for slidable supporting engagement with the enlarged portion of the garment-engaging members.

3. A device as claimed in claim 2 in which said yieldable means includes a coil spring formed substantially rectangularly in outline as viewed along its axis having end elements in engagement with the inner face of the garment-engaging members over substantially an entire turn of the coil.

4. In a garment hanger of the class described, a pair of elongated flat garment-engaging members having an enlarged portion at the upper margin, a horizontal support member provided with a longitudinally extending recess along its under side, an open ended housing into which said garment-engaging members may be telescoped depending from a central portion of the horizontal support member, means to support a rod in said housing in spaced parallel relationship to the horizontal support member, means enabling the rod and garment-engaging members to be telescoped one within another, yieldable means in the housing for urging the garment-engaging members outwardly, said recess in the horizontal support member having in-

wardly turned marginal portions outwardly of the housing for slidable supporting engagement with the enlarged portion of the garment-engaging members.

5. A device as claimed in claim 4 in which said yieldable means includes a coil spring encircling said rod.

6. In a garment hanger of the class described the combination of a horizontal support having a longitudinally extending trackway along its under side; a pair of elongated flat garment engaging members depending from said support, each of said members being provided at its upper edge with trackway engaging means slidably engaged with said trackway; a housing joined to said support at the center thereof between said garment engaging members and depending from said support, said housing opening toward the ends of said support to provide longitudinal channels aligned with said garment engaging members and into which said garment engaging members may telescope, and compression spring means positioned within said housing and engaging said garment engaging members to urge the same outwardly relative to said housing.

7. In a garment hanger of the class described, the combination of a horizontal support having a longitudinally extending trackway; a pair of elongated flat garment engaging members each having trackway engaging means at its upper edge, said trackway engaging means being slidably engaged with said trackway; a housing joined to and depending from said support at the center thereof between said garment engaging members, said housing opening toward the ends of said support to provide longitudinal channels aligned with said garment supporting members and into which said members may telescope; a horizontal rod; means mounting said rod within said housing parallel to said support and aligned with said garment engaging members, each of said members being provided with a longitudinal bore to accommodate an end of said rod as said members are telescoped into said housing, and coil spring means carried by said rod and engaging said garment engaging members to urge the same outwardly relative to said housing.
